UNITED STATES PATENT OFFICE.

GEORGE CHROMY, OF STEWART, MINNESOTA.

DEVICE FOR REMOVING OVERSHOES.

1,290,911.

Specification of Letters Patent.

Patented Jan. 14, 1919.

Application filed May 24, 1918. Serial No. 236,372.

To all whom it may concern:

Be it known that I, GEORGE CHROMY, a citizen of the United States, residing at Stewart, in the county of McLeod and State 5 of Minnesota, have invented new and useful Improvements in Devices for Removing Overshoes, of which the following is a specification.

This invention relates to devices for removing overshoes or rubbers, the object being to provide a simple and efficient device for this purpose which is easily operated and by means of which overshoes may be removed without soiling the hands.

15 A further object is to provide a device of this character which may be adjusted to fit overshoes of different sizes and which may be operated to grip the same at both the toe and heel so that the overshoe will be securely held a provision being made for automatically releasing the overshoe after the same 20 has been removed.

Other objects and advantages of the invention will appear as the following description is read in connection with the accompanying drawings, in which:

Figure 1 is a plan view of a device for removing overshoes constructed in accordance with the present invention;

30 Fig. 2 is an end view of the same.

Referring to the drawings in detail wherein like characters of reference denote corresponding parts, the numeral 10 indicates a pair of toe grips which are oppositely disposed and are each mounted upon the end of a lever 11, the latter being pivoted as shown at 12 upon a base or support 13. Pivotedly secured to the ends of the levers 11 opposite the toe grips 10 are levers 14, the 35 adjacent ends of the levers 11 and 14 being secured through the medium of pivots 15. The outer ends of the levers 14 carry heel grips 16, which are oppositely disposed so as to grip each side of the heel of the overshoe. Both the toe grips 10 and heel grips 45 16 are arcuate shaped so as to conform to the curvature of the toe and heel of the overshoe.

The levers 11 are of angular formation, 50 being bent centrally so as to extend away from their pivots 12, their inner edges 17 which lie between the pivots 12 and 15 forming an inclined cam surface, the opposed inclined surfaces forming substantially an inverted V. Seated within this V and bearing against the surface 17 of each

of the levers 11 is a wedge shaped element 18. Connected to the apex of this element is one end of a rod 19, the opposite end being connected to the adjacent ends of a pair of 60 oppositely extending levers 20, the said levers being pivotally connected together at their point of connection with the rod 19. These levers are pivoted as shown at 21 upon the base or support 13 and carry at their 65 outer extremities pedals 22, the latter being formed with serrated or roughened upper surfaces. The pedals 22 are adapted to be engaged by the foot of the user of the device and when the said pedals are moved inwardly or toward the levers 14, the wedge shaped element 18 will be drawn outwardly to spread the inner adjacent ends of the levers 11 and 14 outwardly and move the toe grips 10 and heel grips 16 inward or toward 70 one another, thereby gripping the overshoe which has been previously placed in position between the grips.

In order to restore the parts to normal position after the gripping operation and to release the overshoe, there is provided a lever 23, which is pivotally mounted as shown at 24 upon the base or support 13. The inner end of this lever is connected to one end of a coil spring 25, the opposite end 80 of the spring being connected as shown at 26 in the wedge shaped element 18. Each of the levers 14 are pivotally connected to the lever 23 at a point upon each side of the pivot 24 by means of a link 27. A movement of the lever 23 upon the pivot 24 will thus serve to move the heel grips away from or toward one another as desired. Mounted upon the base or support 13 is a plate 28, which is provided with teeth 29, the latter 85 being adapted to be engaged by a tooth 30 located upon the under side of the lever 23. This compartment of the said lever being retained in its adjusted position, so that an initial adjustment of the heel grips 16 may 90 be made to fit overshoes of different sizes before the final gripping operation. After the overshoe has been removed the spring 25 will serve to retract the wedge shaped element 18, so that the parts will be restored to 95 normal position. The lever 23 is provided with a serrated or roughened foot rest or pedal 31, the latter having a stirrup 32 so that adjustment of the lever 23 may be made by the foot of the user. It is therefore possible to adjust the heel grips and to move the levers 20 upon their pivots for the pur- 100 110

pose of gripping the overshoe without the use of the hands, the entire operation being made with the other foot.

The invention is susceptible of various changes in its form, proportions and minor details of construction and the right is reserved to make such changes.

Having described the invention, what is claimed is:—

10 1. A device of the class described embodying oppositely disposed toe and heel grips, levers connecting the same, means including a wedge shaped element for operating said levers to move them toward one another and means for automatically restoring the levers to normal position.

15 2. A device of the class described embodying oppositely disposed toe and heel grips,

levers pivotally connected together and to said toe and heel grips, a wedge shaped element for spreading the adjacent ends of the levers to move the toe and heel grips toward one another and means for automatically restoring the levers to normal position.

20 25 3. A device of the class described embodying oppositely disposed toe and heel grips, levers pivotally connected together and to said toe and heel grips, a wedge shaped element for spreading the adjacent ends of the levers to move the toe and heel grips toward one another and spring actuated means connected to the wedge shaped element for automatically restoring the levers to normal position.

30 35 In testimony whereof I affix my signature.

GEORGE CHROMY.
